ICE TRAY

Hazel B. Copeman, Flint, Mich., assignor to
Copeman Laboratories Company, Flint, Mich.,
a corporation of Michigan

Original application February 17, 1937, Serial No.
126,142. Divided and this application October
10, 1938, Serial No. 234,191

4 Claims. (Cl. 62—108.5)

This invention relates to ice trays which are adapted to be placed in the freezing compartment of domestic refrigerators of the mechanical or gas type.

The present application is a division of my copending application Serial No. 126,142, filed February 17, 1937, which has now matured into Patent No. 2,266,007.

In the prior art related to trays for freezing ice in domestic refrigerators, the tendency has been to design trays which form a large number of ice cubes. Many trays have been designed which embody devices and means for removing ice cubes, such as rubber trays and flexible metal trays or trays having flexible covers thereon, but these have either proved to be inconvenient or have resulted in a lengthening of the freezing time due to the low conductivity of rubber or due to the covering of the tray.

The object of the present invention is to provide an ice tray which avoids forming a large number of ice cubes. The present invention contemplates a tray of the type that will freeze water contained therein in a very short freezing time to form a large block of ice, said tray containing means for forming the block of ice so that it may be easily broken up into small blocks or cubes for use or storage of the same.

More specifically the invention relates to the freezing of the complete block of ice in a very short time and scoring or perforating the block as it is frozen so as to make it easy to break the block into small regular portions of ice when desired.

Other features and objects of the invention having to do with details of construction and operation will be further brought out in the following description and claims.

In the drawing:

Fig. 1 is a plan view of the invention showing 40 particularly the top member which is associated with the ice tray.

Fig. 2 is a section taken on the lines 2—2 of Fig. 1 illustrating the relationship of the cover member and ice tray.

Fig. 3 is a section taken on the lines 3—3 of Fig. 1.

Figs. 4 and 5 illustrate modified constructions of the depending members.

Fig. 6 represents a unit to be used in combination with an ice block formed in the tray of Figs. 1 to 3 to break a formed ice block into individual ice cubes.

Fig. 7 is a partial view similar to Fig. 2, showing the use of a soft flexible rubber lining.

The present invention is the type in which a tray sized ice block is provided with tapered perforations which are regularly spaced to mark out ice cubes. Referring to Figs. 1, 2 and 3, a metal tray 34 supports a cover 35, said cover having a large opening 36 so that the cover 35 amounts to little more than a rim around the top portion of the metal tray 34. The metal tray 34 may be lined with a flexible rubber tray 20, see Fig. 7, similar to that shown in my copending application, Serial No. 126,142, filed February 17, 1937, or it may be lined with a permanent coating of wax as in the Hathorne Patent No. 1,932,731, dated October 31, 1933. Supported centrally of the cover 35 and rigidly attached thereto is an elongated U-shaped bar 37. This bar has depending rubber projections 38 embedded in it at intervals along the bar and extending downwardly through the opening 36 in the cover 35 substantially to the bottom of the tray 34. These projections are tapered in such a manner that they are wider at the top than at the bottom and may be mounted in the bar 37 in a number of ways. Fig. 4 illustrates an enlarged view showing how the rubber projection 38 is held in the bar 37. Fig. 5 illustrates another method of supporting the projections 38 where the metal pin 39 serves as a core to the rubber projection 40, said pin extending through the bar 37 and being bent as at 41 to hold the same in place. The preferred cross-section of the projections 38 is rectangular since this particular type of projection may be most easily removed from the completed block of ice. It will be noticed that in Fig. 1 the projections 38 are alternately at right angles to each other to more clearly mark out the corner ice cubes that will ultimately be formed from the ice block made in the ice tray 34. Of course, these projections 38 might be held in position in any number of ways, as for example, they might be formed on a flexible rubber cover.

When the tray 34 is filled with water and frozen a large block of ice will be formed. This block 45 of ice may be removed from the tray 34 either by running hot water over the tray or by pulling on the flexible rubber tray lining if one has been provided. The bar 37 may then be lifted away from the large ice block, and this lifting force will strip the rubber projections 38 from their places in the ice. It will be understood that these rubber projections, when pulled, will reduce in cross-section from the top down and strip themselves from the ice thus permitting an easy removal of the same. The result will be a large

ice block that has perforations at regular intervals in the ice. Ice cubes may be formed from this large ice block either by the use of an ice pick or by placing said complete ice block in a metal tray similar to that shown in Fig. 6 and in which there are upwardly projecting metal prongs located to exactly coincide with the perforations in the ice block. By making these prongs of the slightly larger dimensions than the rubber projections 38 and the corresponding holes or perforations in the ice block, the ice block may be broken into cubes by placing it in tray 42 and exerting a sharp downward pressure on the ice.

What I claim is:

1. The combination with a tray for containing a substance to be congealed or frozen and adapted to be placed in a sharp freezing chamber, of a relatively rigid member having depending projections extending into said tray substantially perpendicular to the bottom thereof to form spaced perforations in a substance frozen in said tray, said depending projections being substantially tapered from said cover and formed of soft flexible rubber.
2. The combination with a tray for containing a substance to be congealed or frozen and adapted to be placed in a sharp freezing chamber, of a cover member having an opening therein, transverse members thereon lying over said opening,

and tapered projections depending from said transverse members, said projections being formed of soft rubber and extending into said tray substantially perpendicular to the bottom thereof.

3. The combination with a tray for containing a substance to be congealed or frozen and adapted to be placed in a sharp freezing chamber, of a cover member provided with a substantially large central opening, transverse members on said cover extending over said opening, tapered soft rubber projections depending from said transverse members substantially to the bottom of the tray, and a soft rubber lining member adapted to be placed between said tray and the substance to be frozen and adapted to loosen said tray from said frozen substance when the lining member is distorted from its normal shape.

4. The combination with a tray for containing a substance to be congealed or frozen and adapted to be placed in a sharp freezing chamber, of a removable skeleton grid member for defining breaking grooves in the contents of the tray, said grid member comprising one or more relatively stiff bars extending across said tray, means associated therewith for locating said bars relative to said tray, and elastic, relatively flexible members on said bars extending into said tray.
